SHOE AND METHOD OF MAKING THE SAME

Fred L. Ayers, Watertown, Mass.

Application March 1, 1935, Serial No. 8,892

17 Claims. (Cl. 12—142)

This invention relates to shoes and to their manufacture.

One object of the invention is to make a shoe which may, if desired, simulate in appearance a single-soled shoe, such as a turn, and yet which may be actually of the two-sole type. When no innersole is employed, the shoe is a single sole shoe with the upper so securely locked to the sole that the use of cement for securing the sole in position is entirely practicable. The shoe, may, if desired, be given an extension sole which may receive ornamentation simulating welt stitching, stitch separating, or wheeling. The shoe is provided with an outer sole member, the upper being lasted in and secured to a rib element which may or may not be carried by an innersole, the sole member being formed to engage and interlock with the upper and rib and to cover and conceal the means by which the upper and rib are secured together. The sole or outer sole is preferably secured as by cement, but the parts are so formed that no roughing operation to cause proper adhesion of the cement to any of the parts is necessary. The sole may, however, be secured by stitching or other means, if desired.

For a more complete understanding of this invention, reference may be had to the accompanying drawings in which

Figures 1 and 2 are plan views, Figure 1 being fragmentary, showing different forms of outer sole which may be used.

Figure 3 is a fragmentary section on line 3—3 of Figure 1.

Figure 4 is a fragmentary perspective, partly in section, of the edge portion of one form of innersole which may be used.

Figure 5 is a view similar to Figure 4, but showing the upper secured to the innersole lip.

Figure 6 is a fragmentary section showing the outer sole and the lasted shoe adjacent to each other preparatory to securing the outer sole in position.

Figure 7 is a fragmentary section showing the outer sole cemented in position and being subjected to pressure while the cement is setting.

Figure 8 is a fragmentary section showing the relation of the innersole, upper, inseam and outer sole in the completed shoe.

Figure 9 is a detail section showing a modified innersole construction.

Figure 10 is a fragmentary perspective of the toe portion of an extension edge shoe made in accordance with this invention.

Figure 11 is a section similar to Figure 3, but showing a modification.

Figure 12 is a section similar to Figure 8, but showing the outer sole of Figure 11.

Figure 13 shows in perspective the forepart of 5 an innersole member of another form.

Figure 14 is a view of the construction of Figure 13, but with a reinforcing layer partly applied thereto.

Figures 17 and 18 are views similar to Figures 8 and 12, respectively, but employing the innersole of Figures 13 and 14.

Figure 19 is a fragmentary section through the edge portion of an innersole of another form.

Figures 20 and 21 are views similar to Figure 19, but showing the upper stitched to the innersole and before and after the trimming operation, respectively.

Figure 22 is a fragmentary perspective showing the use of a separate outersole lip member for interlocking with the upper and innersole.

Figure 23 is a section similar to Figure 12, but 25 employing the construction of Figure 22.

Figure 24 is a view similar to Figure 23, but illustrating a modification.

Figure 25 is a perspective with parts broken away, showing a method of producing a rand 30 strip such as is shown in Figures 22 and 23.

Figure 26 is a section similar to Figures 3 and 4, but showing a further modification.

Figure 27 is a plan view showing an upper-receiving rib temporarily attached to a last and 35 permanently attached to a shank piece.

Figure 28 is a detail section on line 28—28 of Figure 27.

Figure 29 is a view similar to Figure 28, but showing the upper lasted over and secured to 40 the rib.

Figure 30 is a detail section similar to Figure 29, but showing the upper trimmed and the sole prepared for attachment.

Figure 31 is a view similar to Figure 30, but 45 showing the sole attached and the shoe subjected to sole-securing pressure.

Figure 32 is a somewhat diagrammatic perspective showing a last with a temporary innersole or locating piece secured thereto in conjunction with a shank piece and an upper-securing member, the shank piece and member being intended to be attached to the innersole or locating piece.

Figure 33 is a somewhat diagrammatic central 55

longitudinal section through the shoe and last employing the construction of Figure 32 and showing the last partly removed, taking with it the temporary innersole or locating piece.

5 Figure 34 is a detail section through the toe portion of a shoe and last employing a sock lining to which the upper attaching element is permanently secured and showing in dotted lines the last partly removed.

10 Figures 35 and 36 are views somewhat similar to Figures 29 and 30, respectively, but showing a modification.

15 Figures 37 and 38 are detail sections somewhat similar to the upper parts of Figures 30 and 36, respectively, but showing a further modification.

15 Figure 39 is a fragmentary perspective of a lasted shoe showing still another modification.

This application is a continuation in part of my application Serial No. 727,244, filed May 24, 20 1934, for Shoe and method of making the same.

Referring to Figure 4 of the drawings, at 1 is indicated an innersole which may, if desired, be provided with a reinforcing layer 2 of canvas, or the like, in accordance with common practice.

25 As shown this innersole is cut inwardly at its edge at 3 to form a feather or outward extension element 4 about its margin and adjacent to its lower face. This innersole may be tacked to the last in the usual manner and the upper materials, comprising the outer 5 and the lining 6, may then be drawn over and lasted and secured to the element 4, as shown in Figure 5, as by a line of fastenings, shown as comprising an inseam 7. The element 4 and the margins of the upper materials are then trimmed off, as shown in Figure 6, the upper materials extending outwardly somewhat below the inseam and forming an outwardly projecting flange 8, the action of the trimming knife in the direction of the 40 arrow aiding in thus shaping the parts. Since the securing of the upper material is nearer the edge of the innersole than in most prior constructions, the upper stock may be cut with less lasting allowance so that there is a saving 45 of material.

In Figures 5 and 6 enchainment of the inseam stitches is shown as positioned on the inner face of the innersole lip and this will usually be the preferred arrangement because it offers less 50 amount of thread to be concealed from view in the finished shoe. Certain types of sewing machines may be used to position the stitches in this manner, although the more usual types of inseam stitches will cause the enchainment to 55 occur on the outside of the upper materials.

Where it is desired to use a usual form of inseam stitcher in such a manner that the enchainment will be on the inside the innersole may be constructed as shown in Figure 9 with 60 a marginal feather or element 9 extending outwardly beyond the normal outline of the inner sole as at 10, whereupon the shoe may be presented to the inseam stitching machine after the manner disclosed in my Patent No. 1,920,338 65 granted August 1, 1933. After the parts have been sewed together, the extension feather 9 is trimmed off so that the lasted shoe appears as shown in Figure 6. On whichever side the enchainment lies, however, the stitches pass 70 through the feather substantially crosswise of the fibers whether the innersole be made of leather or of fibrous material felted together as on a paper machine, so that the stitches are strongly held even with the lighter grades of 75 stock.

In Figures 1 and 2 are illustrated two forms of outer sole suitable for this invention. In the form shown in Figure 1, the outer sole 12 is channeled on its upper face toward its margin about the forepart only to form a lip 15, which is turned up, as shown in Figure 3. The outer sole of Figure 2 is the same as that of Figure 1 with the exception that the channeling is carried also through the shank portion of the sole, instead of throughout the forepart only. 10

The lip 15 may be turned upwardly so as to facilitate the presentation of the sole to the lasted shoe, as shown in Figure 6, with the trimmed portion of the feather 4 and the margins of the upper materials just inwardly of the lip 15. One or both parts are coated with permanent cement from the outer edge of the inseam stitching 7 inwardly to the desired distance from the feather 4, and are then preferably, while the cement is still soft, placed together and held under heavy 20 pressure, as shown in Figure 7. This pressure may be exerted in the usual manner, as by means of an inflated air cushion 20, and it is preferable to apply the pressure in a manner to cause the marginal portion of the outer sole 14 to be curved 25 upwardly, this turning the outwardly turned margins of the upper materials 5 and 6 and the feather 4 outwardly and beneath the lip 15, which is laid down beneath the upper materials above the inseam stitch line, and into contact with the 30 threads at the outer face of the inseam stitching.

This method of cementing avoids the necessity, present in the manufacture of most types of cemented shoes, of applying a solvent to the previously cement-coated and dried confronting 35 surfaces of the parts to be attached, and is further desirable with the present shoe construction in order that the outer sole lip and the cooperating parts of the lasted shoe shall be sufficiently flexible, when these parts are assembled, 40 to properly interengage and assume their desired relations in the shoe.

It may also be found desirable when making the inseam to employ a stitching needle of relatively large size so that the cement may squeeze 45 into the holes around the stitches, thus to penetrate into the material of the stitches and strengthen them as well as to cement their various adjacent parts together and to the stitches. Staples or other equivalent fasteners might, of 50 course, be used in place of inseam stitching, if desired, though because cement will adhere well to stitching this will usually be preferable.

When the cement is set and pressure is removed, the shoe sole may be leveled so that the 55 outer sole margin returns to a substantially flat condition and it is thereafter subjected to the usual trimming and setting operations which bring the parts to the condition shown in Figure 8 with the lip 15 returned to a substantially flat 60 condition and overlying the outwardly projecting upper materials below the inseam stitching, thus firmly locking the parts together and entirely concealing the inseam stitches from view. The confronting faces of the inner and outer soles 65 are in direct contact so that no sole filler is required and the cemented portions of the shoe are all outside of the area contacted by the foot. Where a canvas might otherwise directly contact with a sole member a piece of soft thin material such as flannel may be interposed, if desired, to prevent squeaking. Since no stitches or tack holes appear on the inner face of the innersole, it is not necessary to use a sock lining if it be desired to omit it, or, as may later appear, the in- 70 75 75

innersole itself may be of a thinness and of a material that will serve as a sock lining. Particularly where the cement is not caused to pass into the needle holes, the shoe constructed in accordance with this invention has the breathing properties of an ordinary sewed shoe since there is no cement above the inseam stitch line. This obviates one of the disadvantages often experienced with types of cemented shoes heretofore used in which there has often been found a tendency to "draw" the feet due to the lack of ventilation or "breathing" around the sole of the shoe. Due to the interlock between the outer sole and lasted shoe also, the proper laying of the outer sole is facilitated since the interlocking of the lasted shoe locates the position of the outer sole, which cannot thereafter slip out of position laterally—a common difficulty in the manufacture of other forms of cemented shoes. Leveling of the shoe sole thereafter breaks up the cement without, however, weakening the bond so that the sole is more flexible than that of a cement shoe as heretofore constructed.

If desired the completed shoe may have an extension edge as shown at 21 in Figure 10, which may be finished to simulate a welt or other usual multiple-soled shoe, and it may be provided with a line of stitching or stitch simulations, or the upper margin of this extension may be stitch separated, wheeled, or otherwise ornamented. Such finishing operations may be performed after the outer sole has been applied, as the interlock of the outer sole with the other parts is so secure that no damage to the bond therebetween is to be feared. This is not a feasible practice with cement process shoes as usually constructed heretofore. Such operations on the shoe constructed in accordance with this invention act to insure the proper laying of the outer sole lip in position and make the wrapping or curving of the margin of the outer sole in the press, as shown in Figure 7, of less importance. Of course, by providing a support for the upper face of the outer sole margin, as shown in Figure 31, to take the thrust of the outer sole engaging pressure element, such curving may be entirely avoided. The pyroxylin cements now commonly employed in cemented shoes, require for best results that the parts to be cemented be held under pressure for a time after they have been assembled, the cement being in tacky condition, and by so positioning the parts that the confronting faces of the sole lip and the lasted shoe element interengaged therewith are positioned substantially wholly inwardly beneath the shoe upper above the sole, the last affords sufficient internal support to cause the outside presser element to do all the pressing required for proper securing of the parts together. A mock welt can be secured on the upper face of this outer sole, if desired, as by through and through stitches.

Still another construction of extension edge is shown in Figures 11 and 12. Referring to Figure 11, a mock welt 25 is stitched as at 28 to the lip 26 of the outer sole 27, which is preferably thinner than the lip 15 of Figure 3. This stitching may be done with either a chain or lock stitch machine, the enchainment where a chain stitch is employed being preferably on the inner face of the lip 26. The outer sole with the mock welt is then secured to the lasted shoe as heretofore described, the lip and mock welt being ultimately flattened out as shown in Figure 12, so that the stitch line 28 shows on the top face of the mock welt simulating the outer sole stitching in a welt

shoe. The stitching may be sunk down into the welt, if desired, as is also common practice in welt shoes and the upper face of this welt may be otherwise ornamented and finished to simulate welt shoe construction. This embodiment of the invention may be used to give a thick edge effect:

In Figures 13 to 18 constructions particularly suitable for use when a flexible soled shoe is desired are illustrated. A relatively thin innersole blank 30 is channeled about its margin to form the upper and lower portions 31 and 32 shown in Figures 13 to 16 and has the central portion of its forepart cut out as shown at 33 to leave a marginal rim 34. The inner margin of this rim is skived off as at 35 on its lower face (Figure 15). Cement is then applied to this lower face and the blank is then stuck in face to face relation to a permanent reinforcing layer 36 (Figures 14 and 16) which may be of canvas or the like. This reinforcing layer is cut either before or after the blank is applied thereto, and, if desired, to extend somewhat beyond the margin of the blank to form with the blank element 32 a portion to receive the inseam stitches similar to the construction shown in Figure 9. The innersole thus prepared is employed in the same manner as heretofore described, the upper materials being lasted over and secured to the stitch-receiving element of the innersole as by the stitch line 37, after which the parts are trimmed. The outer sole with its marginal lip 15 is then applied and cemented as heretofore described so that the outer sole and lasted shoe interlock, the outer sole lip extending inwardly over the outwardly extending upper material 35 margins, as shown in Figure 17 or 18, Figure 17 showing no mock welt as in Figure 8, while Figure 18 shows a mock welt 25 as in Figure 11.

The cut edges of the upper materials, the adjacent portion of the innersole and the face of the outer sole where it is channeled, and also the thread of the inseam stitching, provide surfaces which will take the cement properly without any roughening up which is found necessary in the case of cement process shoes as ordinarily constructed where the cement is required to adhere to the outer faces of the upper materials. While the upper at its margin may be roughed, if desired, this is not depended upon to produce a proper bond between the lasted shoe and the outer sole.

In order to further effect a cement bond between the parts, the inseam thread may be pretreated with cement, as by being passed through liquid cement and allowed to harden, and then just before the stitching is effected being passed through a cement solvent which may be positioned as is the usual wax pot of a wax thread sewing machine. In addition or in lieu of cement, the outer sole may be secured as by McKay stitches 39, as shown in Figure 8.

It is also possible to employ an innersole having a stitch-receiving rib similar to that commonly employed in welt shoes. Figure 19 shows such an innersole having a double lip 40 formed by both inwardly and outwardly channeling the innersole about its margin, this lip being reinforced in the usual manner on its inner side by a fabric layer 41. Figure 20 shows a single lip 42 formed by outwardly channeling the innersole, this lip likewise being reinforced with fabric 41. With either of these constructions the inseam trimming, if done in an outward direction, as shown by the arrow in Figure 21, produces a sufficient outward extension of the parts as at

43 beyond the outer face of the inseam stitches to produce an interlock with the outer sole as previously described. Any innersole and upper arrangement which will produce a construction 5 larger at its lower end than above so as to provide an interlock with the outer sole may be used.

It may sometimes be found desirable to initially form the interlocking portion of the outer 10 sole as a separate part which is secured to the outer sole either before or after the outer sole is applied. Such part may be a marginal rand cut from the outer sole 45 as shown at 46 in Figure 25. After the removal of this rand the 15 outer sole edge may be further thinned, as shown in Figure 22 at 47. This rand or other piece of similar cross section may, if desired, be provided with ornamental stitching as shown at 48 in Figure 22, or it may be secured to the outer sole 20 by stitching 50 before the outer sole is applied to the shoe in the manner shown in Figure 26, and its inner edge at 51 raised to facilitate the insertion beneath it of the mating interlocking portion of the lasted shoe. The stitch 50 may be 25 chain or lock stitch, and it may be ornamental on the lower face of the sole as well as on the upper face of the strip 50, if desired. If desired, also, the separate strip may be cut straight and it may be temporarily secured in upstanding 30 position about the margin of the outer sole blank, as shown in Figure 24 at 55, and its upper edge portion 56 in-turned over the top of the outer sole where it may be cemented when the outer sole is applied to the shoe. The other part extending outwardly of the edge of the outer sole blank may be trimmed off later as at the dotted line a—a, leaving the portion 56 as shown in 35 Figure 23 interlocking with the upper extension and concealing the inseam stitches similarly to 40 the integral lip 15 shown in Figure 8.

This general method of attaching an outer sole member may be employed to advantage in shoes of the single sole type, that is, in which no innersole is employed. Constructions of this 45 nature are illustrated in Figures 27 to 39. Referring first to Figures 27 to 30, at 60 is shown a last to the sole face of which about its margin is temporarily secured an element 61 in the nature of a stitch-receiving rib. This element 50 61 may be secured as by the use of rubber cement directly to the last and may in addition be temporarily secured at intervals, as by tacks 62. As shown it is formed of a pair of angle strips 63 and 64 secured together to form a flanged 55 lip 65 to receive the stitches, the flanges 66 and 67 being formed to engage with the last. It might, however, be otherwise constructed so long as it is so made as to present a portion to which the upper materials may be secured and 60 to have sufficient bearing on the last to facilitate temporary securing in a sufficiently secure manner. Rearwardly from the break line of the last, the strip 61 may be secured permanently to the lower face of a shank piece 68. This may 65 be of usual construction having a portion extending down into the shank of the last as at 680 and a heel portion 69. The upper materials are lasted over in the usual manner and secured as by stitching at 70 to the element 65 70 after which the margins are trimmed, and where temporary lasting tacks are employed, such as 62, these are pulled before the sole is applied. This sole, corresponding to the outer sole of the constructions previously described, is 75 shown at 75, and preferably it is recessed about

its margin as at 76 to form a central thickened portion 77, as this central portion tends to hold the marginal portions of the upper and stitching rib outwardly where they belong in the finished shoe, taking somewhat the function of the innersole in accomplishing this in the double-soled shoes previously described. At the outer portion 5 of this marginal recess 76, this sole is provided with the marginal inwardly extending lip 78, defined by the wedge shaped channel therebelow, the lip, as shown, being integral with the sole member. It might, however, be made in any of the forms hereinbefore illustrated, separately and thereafter attached.

Figure 30 illustrates a somewhat different manner of treating the parts to form the interlocking connection between the lasted shoe and the sole 70, which, however, is applicable in the attaching of the outer sole to a lasted shoe which is provided with an innersole as previously described. In accordance with this method the trimmed upper materials are turned downward instead of outward, and the entire margin of the sole member throughout the length of the lip 78 is molded downwardly, if desired while in 10 temper, from the dotted line into the full line position. The parts are thus assembled and the margin of the sole returned to or slightly above the horizontal position under pressure, this forcing the trimmed upper margins outwardly into 15 the channel of the sole and the lip 78 over these margins and against the outer face of the upper and the outer face of the inseam stitches, as shown in Figure 31. The proper formation 20 may be aided by the use of an anvil member 80 25 engaging the top face of the sole margin and against which the sole is pressed. The sole 75 30 may be applied, however, in the manner heretofore described when shoes provided with innersoles are employed and the parts are subjected to 35 pressure. The flange 66 will be cemented to the sole 75. When this is done the outwardly extending upper margin parts may be pre-treated 40 with cement which is allowed to harden and stiffen the parts before the sole is applied. When 45 the parts have been secured sufficiently, the last is removed, the rib 61 separating from the last, and remaining behind so that the shoe appears as illustrated in Figure 31 with the stitch-secur- 50 ing element 61 at the margin of the upper and cemented to the sole 75, the marginal flanges 66 and 67 of the member 61 being all that appears 55 inside the shoe on the upper face of the sole member 75, the out-turned edges of the upper being in interlocking engagement with the sole 75 so that the parts are firmly secured. The flange 67 acts to hold the upper to the outer line of 60 the last after the last has been removed and helps to cover the line of inseam fastenings. At the shank and heel portion of the shoe the shank piece is positioned so that these parts of 65 the shoe are reinforced, while the forepart only presents a single sole. Where the strip 61 is secured to the last by rubber cement and pyroxylin cement is employed to secure the sole in 70 position, the fumes from the solvent of the pyroxylin cement act on the rubber cement and cause it to lose very much of its adhesive quality, so that the later removal of the last leaving the strip 61 behind is greatly facilitated.

In any case where it may be desired to do so, as where it may be impracticable to secure the element 61 directly to the face of the last, it may be temporarily secured to an innersole member shown in Figures 32 and 33 or locating piece 75

85. As shown in these figures, this innersole member is arranged in the forepart only since as it will usually be desired to employ a permanent shank piece 68, an extension further rearwardly of this innersole would be of no value. It may be secured permanently to the last as by tacks 86, both inwardly and outwardly of the stitch-receiving rib 61, if desired, and after the upper and sole 75 have been secured, as described in connection with the construction shown in Figures 27 to 31, the last, together with the innersole 85, is removed from the shoe, leaving the upper-securing strip and the shank piece attached to the sole.

15 Instead of employing a temporary innersole in this manner, a relatively thin material suitable for use as a sock lining may have the upper-securing rib or lip permanently attached thereto. Such a construction is shown in Figure 34 20 in which a thin piece of fabric, or the like, at 90, which may serve as a sock lining and which is of the shape of an innersole, is temporarily secured to the sole face of the last, and has secured thereto the upper-receiving lip or element 25 such as 61. The shoe having been lasted and the sole 75 secured thereto, as previously described, on the last being removed, the member 90 is left in place to serve as a sock lining.

Instead of forming the outwardly extended 30 margin of the lasted shoe for interlock with the sole member of the upper margins, this interlocking portion may be otherwise formed as shown, for example, in Figures 35 to 38, whether or not an innersole is to be employed in the forepart of the finished shoe. In Figure 35 the inseam stitches 100, which secure the upper materials to the sole-securing element 101, also pass through a thin narrow strip 102 secured outwardly of the shoe upper 103 and after the inseam trimming operation the upper edge of this strip 102 is turned outwardly by running a suitable tool therearound between its inner face and the adjacent face of the upper to form an outward extension 104 (Figure 36), which may be 40 engaged beneath the sole lip 77 and interlock therewith. This strip 102, since it comes out above the stitch line serves to entirely conceal the stitching and even if the lip 67 should not be laid in place thoroughly, no inseam stitching can 45 appear in the finished shoe.

In Figures 37 and 38 a construction is shown in which the inseam stitches themselves are employed to form this outwardly extending element for interlocking engagement with the sole. 50 Where this is done, the inseam stitching at 110 is preferably arranged with the stitch interlock on the outside, thus to present a substantial mass of thread as at 111, and the thread may be heavier than that which would ordinarily be used 55 in the other constructions herein illustrated. This thread may then be mashed down on its upper face to form a substantial outward extension at 112 shown in Figure 38, and the wetting of this portion of the shoe with a cement or a 60 cement solvent which will tend to soften the stitch material somewhat may be used to aid in conditioning the thread so that this shaping operation can be done more easily. This extension 112 is then usable for that portion of the 65 lasted shoe which interlocks with the in-turned lip on the upper face of the sole member. This sole member may either be an outer sole, where an innersole is employed, or be the single-sole where no innersole appears in the forepart of the finished shoe.

One of the great advantages of the shoe constructions heretofore illustrated lies in the fact that the interengagement between the sole and the lasted shoe is predetermined by the position of the sole lip. This makes it possible to pre-cut the sole to substantially finished size, since it cannot slip laterally when being applied due to the interengagement between the sole lip and the outwardly extending portion of the lasted shoe which engages therewith, and this cutting being done while the sole is flat and the upper materials are not in the way can be done by machinery with great uniformity. In other types of shoes where the sole must be trimmed to finished size after application to the shoe, this trimming, particularly in the shank portion of the shoe, is determined by the skill of the operator in guiding the shoe to the trimming means, and in practice results in considerable lack of uniformity in different shoes. It might also be noted that in the constructions herein shown the main cement bond is between the lasted shoe and the sole inwardly of the lip, but this is protected by the interengaging and secured lips from entrance of moisture and other foreign matter which in other types of cemented shoes has in time seriously affected the cement bond between the sole and the other parts.

From the foregoing description of certain embodiments of this invention, it should be evident to those skilled in the art that various changes and modifications may be made without departing from the spirit or scope of this invention as defined by the appended claims.

I claim:

1. A shoe having a sole presenting at its outer edge the edge of the sole stock and having an inwardly extending marginal lip on its upper face attached thereto adjacent its outer edge, and means comprising upper materials and an element to which said upper materials are lasted and secured, said means presenting an outwardly extending part interposed between the inner edge of said lip and the upper face of said sole and terminating inwardly of the attachment of said lip to said sole, the adjacent faces of said part and lip being secured together and positioned substantially wholly inwardly beneath the shoe upper above said sole.

2. A shoe having a sole presenting at its outer edge the edge of the sole stock and outwardly channeled to form an inwardly extending marginal lip on its upper face attached thereto adjacent its outer edge, and means comprising upper materials and an element to which said upper materials are lasted and secured, said means presenting an outwardly extending part interposed between the inner edge of said lip and the upper face of said sole and terminating inwardly of the attachment of said lip to said sole.

3. A shoe having an innersole, upper materials lasted in and secured to said innersole and having their margins outwardly turned below their securement to said innersole, and an outer sole channeled toward its margin on its upper face to form an inwardly extending lip, said lip overlying said outwardly turned margins and concealing the securement of said upper to said innersole.

4. A shoe having an innersole provided with a marginal feather on its lower side, upper materials lasted in and stitched to said feather, said feather and the margins of said upper materials extending outwardly, and an outer sole cemented to said innersole and upper materials and having an integral inwardly extending lip overlying said 75

outwardly extended upper materials and concealing said stitching.

5. A shoe having an innersole provided with a marginal feather on its lower side, upper materials lasted in and stitched to said feather, said feather and the margins of said upper materials extending outwardly, and an outer sole cemented to said innersole and upper materials and having an integral inwardly extending lip overlying said 10 outwardly extended upper materials and concealing such stitching, said inner and outer soles being in contact inwardly of said lip.

6. A shoe having an innersole provided with a marginal feather on its lower side, upper materials lasted in and stitched to said feather, said feather and the margins of said upper materials extending outwardly, and an outer sole cemented to said innersole and upper materials and having an integral inwardly extending lip 15 overlying said outwardly extended upper materials and cemented to and concealing such stitching.

7. A shoe having an innersole, upper materials lasted in and secured to said innersole and having their outer margins outwardly turned below their securement to said innersole, an outer sole channeled toward its margin on its upper face to form an inwardly extending lip, and a mock welt secured to said lip by a line of stitches, said lip 30 and mock welt overlying said outwardly turned margins, and said line of stitching showing on the upper face of said welt and simulating in appearance the outer sole stitching of a welt shoe.

8. The method which comprises lasting a shoe 35 and securing the margins of the upper to a reinforcing element extending about the margin of the sole face of the last to leave a projecting element, applying a sole member to the lasted shoe with an inwardly extending lip about its margin 40 overlying said element, subjecting the parts to pressure to lay the lip and extend the element thereunder, and then removing the last.

9. The method which comprises temporarily securing an upper reinforcing element to the sole 45 face of a last adjacent to its margin, lasting the upper materials over and securing them to said element to form therewith a portion having a projecting flange, securing a sole member with an inwardly projecting marginal lip to the lasted 50 shoe with said lip overlying said flange, and thereafter removing the last leaving said element attached to said upper and sole.

10. The method which comprises lasting and securing the margins of the shoe upper in position 55 adjacent to the sole face of the last and forming adjacent to such securement an outwardly extending element, forming an inwardly extending marginal lip on the upper face of a sole member for engagement over said element and 60 while maintaining said sole member of substantially its original size, and positioning and securing said sole on the lasted shoe with said lip overlying said element.

11. The method which comprises lasting and 65 securing the margin of a shoe upper in position adjacent to the sole face of the last and forming adjacent to such securement an outwardly extending element, shaping a sole blank to substantially finished size, forming an inwardly extending 70 marginal lip on the upper edge of said blank for engagement over said element, and positioning

and securing said blank thus prepared on the lasted shoe with said lip overlying said element.

12. The method which comprises lasting and securing the margin of a shoe upper in position adjacent to the sole face of the last and forming 5 adjacent to such securement an outwardly extending element, outwardly channeling the upper face of a sole member of substantially finished size about its margin to form an inwardly extending marginal lip, and then positioning and 10 securing said sole member to the lasted shoe with said lip overlying said element.

13. The method which comprises lasting and securing the margin of a shoe upper in position adjacent to the sole face of the last and forming 15 adjacent to such securement an outwardly extending element, securing to the upper face of a sole member about its margin a strip of material forming inwardly of its securement an inwardly extending lip, and securing said sole member to the lasted shoe with said lip overlying said element.

14. The method which comprises lasting a shoe and securing the margins of the upper to a marginal feather at the lower face of an innersole, 25 outwardly channeling an outer sole and turning the channel lip outwardly, cementing said outer sole to the lasted shoe with said feather and upper margin inwardly of said lip and with said lip covering the line of inseam securement, and then subjecting the parts to pressure in a direction to lay the lip down and to extend said feather and upper margin outwardly beneath said lip.

15. The method which comprises lasting a shoe and securing the margins of the upper to a marginal feather at the lower face of an innersole, 35 outwardly channeling an outer sole and turning the channel lip outwardly, cementing said outer sole to the lasted shoe with said feather and upper margin inwardly of said lip and with 40 said lip covering the line of inseam securement, pressing the lip down over the upper margins and feather, permitting the cement to harden, and then finishing the portion of said outer sole extending outwardly beyond the upper.

16. The method which comprises lasting a shoe and securing the margins of the upper to a reinforcing element extending about the margin of the sole face of the last to leave a downwardly projecting element, molding the marginal portion 50 of a sole member having an inwardly extending marginal lip on its upper face to raise said lip, applying said sole member to the lasted shoe with said lip outwardly of said projecting element, and then pressing said molded margin 55 to close said lip over said element and extend said element outwardly beneath said lip.

17. The method which comprises lasting a shoe and securing the margins of the upper to a reinforcing element extending about the margin of the sole face of the last to leave a downwardly projecting element, molding the marginal portion 60 of a sole member having an inwardly extending marginal lip on its upper face to raise said lip, cementing said sole member to the lasted shoe with said lip outwardly of said projecting element, and then pressing said molded margin 65 to close said lip over said element and extend said element outwardly beneath said lip.
